PERMANENT WAVING DEVICE

William H. Brown, Bedford, Ohio

Application April 17, 1936, Serial No. 74,976

10 Claims. (Cl. 132—33)

This invention relates to a permanent waving device and particularly to a novel form of hair gripping mechanism generally known as a protector clamp. Objects of the invention are to provide a simple form of protector clamp which can be applied to a strand of hair either adjacent the scalp or at any point along the strand sufficiently spaced from the distal end thereof to permit starting the curl on the curler rod; to provide for applying a regulated tension to the curl as it is being wound; at the same time preventing disarrangement of the strand which would occur if a sliding clamp were applied; and to provide a simple means for clamping the gripping parts together.

Other objects will be in part apparent and in part pointed out hereinafter in connection with the accompanying drawing wherein Fig. 1 is a plan view showing the conventional curler rod in position on the novel protector clamp; Fig. 2 is a plan section taken centrally through the rollers forming the gripping jaws; Fig. 3 is an end elevation showing the curler rod in place and the relation of the parts to the shield which is conventionally interposed between the protector clamp and the scalp; Fig. 4 is a detail view indicating one method of applying the rollers in gripping relation to a strand of hair; and Fig. 5 is a development of the stamping which forms the supporting frame for holding the rollers. Fig. 5 is drawn to approximately full size while the other views are drawn to approximately double size.

In the drawing, the numeral 10 indicates generally the framework stamping which consists of a connecting portion 11 adapted to hold the end portions in proper relation, and end pieces provided with curler rod receiving notches 12 and 13 and openings 14 and 15 for receiving a bolt upon which one of the rollers is journaled, as well as openings 16 and 17 for receiving the shaft of the other roller. The notch 12 is provided with a tooth 18 adapted to act as a stationary pawl to engage the ratchet teeth 19 of the curler rod 20 and is relieved at the point 21 opposite the tooth 18 to permit motion of the curler rod for ratcheting and release. The notch 13 conforms closely to the smooth end 22 of the curler rod 20 whereby to facilitate holding the curler rod in proper relation to the protector clamp as the assembly is being wound toward the scalp. The opening 15 is squared to receive the square shoulder 23 of the bolt 24 which acts as a shaft upon which the roller 25 may rotate. The bolt 24 passes through the openings 15 and 14 and is provided with a nut 26. The roller 25 rotates on the bolt 24 and is composed of substantially

rigid material, preferably of poor heat conducting qualities and is of a length to engage the adjacent portions of the stamping 10 and to be tightened therebetween by the nut 26 whereby to secure a regulated braking action.

The stamping 10 is provided with outwardly pressed guide channels 27 surrounding the openings 16 and 17 and extending to the edge of the stamping 10 as indicated in Figs. 2 and 5. The openings 16 and 17 receive the ends of a shaft 28 upon which is received a roller 29 which may be of rubber or other similar compressible material, preferably having low heat conducting qualities. The roller 29 preferably is not movable with respect to the shaft 28 but is fixed thereto and moves therewith. One or both ends of the shaft 28 may be provided with eccentrically positioned cylindrical projections 30 preferably tangent to the main portion of the shaft. The shaft 28 may also be provided at one or both ends with saw kerfs 31 adapted to permit the insertion of a prying tool such as a smoothing pin 32.

In operation the hair may be divided into blocks and strands passed through a shield 33 which may be of usual construction, although preferably is somewhat rigid whereby to resist wrinkling. The protector clamp with the nut 26 loosened and the roller 29 removed is then placed against the strand and the roller 29 is pushed into place, the ends of the shaft 28 moving along the guides 27 until the portions 30 are received in the openings 16 and 17. With the parts in this condition, the rollers will not grip the strand sufficiently tightly and it will be necessary to move the parts into the position indicated in Fig. 2. This may be accomplished in one of two ways, the nut 26 may be tightened somewhat and the whole clamp moved along the strand toward the scalp by manually rotating the roller 29. When this roller has rotated through a half turn due to the eccentricity of the projections 30 and the continuity of these projections with the shaft 28 at one point, the rollers will have been tightened to the extent indicated in Fig. 2 and the ends of the stamping 10 which were previously flared, will move to the position indicated in Fig. 2, whereupon the rollers may rotate to any extent with the same degree of tension. Alternatively, the shaft 28 may be pried into the position shown in Fig. 2 by the insertion of a prying tool 32 into the kerfs 31 and rotating the same away from the shaft 24 whereby to force the shaft 28 and roller 29 against the roller 25 and urge the edge portions of the stamping 10 to move to the position indicated in Fig. 2. Should a larger size

prying tool be desired, the kerfs 31 may be somewhat wider and the portions of the stamping adjacent the open side of such kerfs as seen in Fig. 2 may be notched whereby to receive such 5 larger prying tool.

When it is desired to wind a curl while applying a regulated tension thereto during the winding, the protector clamp is attached to the strand near the distal end thereof, the nut 26 tightened 10 to provide the desired degree of braking, the curl started on the curler rod and the curler rod rotated in the usual manner with one hand while the protector clamp and curler rod are held in assembled relation by the other hand. When it 15 is desired to wind a curl in the usual manner, the protector clamp is applied near the scalp and the curl wound manually until the curler rod approaches the protector clamp after which tightening is effected in the usual manner. It 20 is usually desirable, where the curler is being tensioned at all times during winding, to tighten the nut 26 still further at the time the rollers 25 and 29 contact the shield 33 although this may not be necessary where the tension applied during 25 the winding has been such that no further tightening is necessary after the protector clamp engages the shield.

By the above described construction, I am able to secure an even tension and at the same time 30 to prevent any bunching or tangling of the hair between the protector clamp and the scalp. It will thus be seen that I have provided a device which is well adapted for its intended purpose and while I have shown and described the present 35 preferred embodiment of my invention, I wish it understood that the same may be realized in different constructions and I therefore do not wish to be limited except in accordance with the scope of the appended claims and the prior art.

Having thus described my invention, what I claim is:

1. A permanent waving device comprising, in combination, a pair of rotatable rollers, means for holding said rollers in position to clamp a strand of hair therebetween, means for applying a rotation resisting force to one of said rollers and means for winding a strand of hair clamped between said rollers and causing it to pass between said rollers as it is being wound.

2. A permanent waving device comprising, in combination, a pair of rotatable rollers, means for holding said rollers in position to clamp a strand of hair therebetween, means for applying a regulable rotation resisting force to one of said rollers and means for winding a strand of hair clamped between said rollers and causing it to pass between said rollers as it is being wound.

3. A hair waving device comprising, in combination, a frame, clamping means comprising parallel rotatable rollers journaled in opposed portions thereof and between which a strand of hair may pass, means for urging said rollers into hair gripping relation to each other and rotatably supporting them in such relation, means forming a portion of said framework for rotatably supporting a curler rod upon which the hair is wound, and means for applying a regulable rotation resisting force to at least one of said rollers.

4. A hair waving device comprising, in combination, a frame, clamping means comprising parallel rotatable rollers journaled in opposed

portions thereof and between which a strand of hair may pass, means for urging said rollers into hair gripping relation to each other and rotatably supporting them in such relation, means forming a portion of said framework for rotatably supporting a curler rod upon which the hair is wound, and means for applying a regulable rotation resisting force to at least one of said rollers, said framework comprising a single sheet metal element.

5. A hair waving device comprising, in combination, a pair of jaws comprising rotatable rollers, one thereof being provided with a central shaft, means including a connecting member having a shaft receiving opening formed therein for connecting said jaws at their ends, and means for urging said jaws into hair gripping relation to each other, said last means including a cam projection on an end of said shaft having one point on its cam surface approximately continuous with the surface of said shaft and the remainder within the extension thereof said first means being provided with elements adapted to rotatably support a curler rod.

6. A hair waving device comprising, in combination, a pair of jaws comprising rotatable rollers, one thereof being provided with a central shaft, means including a connecting member having a shaft receiving opening formed therein for connecting said jaws at their ends, and means for urging said jaws into hair gripping relation to each other, said last means including a reduced extension on an end of said shaft and a groove traversing said end portions of said shaft and said extension whereby a prying tool 35 may be inserted for tightening said roller jaws on a strand of hair said first means being provided with elements adapted to rotatably support a curler rod.

7. A permanent waving device comprising, in combination, a pair of rotatable rollers, means for holding said rollers in position to clamp a strand of hair therebetween and means carried by said holding means for supporting a curling rod thereon.

8. A permanent waving device comprising, in combination, a pair of rotatable rollers, means for holding said rollers in position to clamp a strand of hair therebetween and means carried by said holding means for supporting a curling rod in spaced relation to said rollers thereon, said holding means also including means for applying a rotation resisting force to one of said rollers.

9. A permanent waving device comprising, in combination, a pair of rotatable rollers, means for holding said rollers in position to clamp a strand of hair therebetween and means carried by said holding means for supporting a curling rod thereon in spaced relation to said rollers, said holding means also including means for applying a regulable rotation resisting force to one of said rollers.

10. A permanent waving device, comprising, in combination, a pair of rotatable clamping rollers, holding means including a substantially rigid frame portion for holding said rollers in position to clamp a strand of hair therebetween, said framework including curling rod supporting means at each end thereof.
